UNITED STATES PATENT OFFICE.

WILLIAM A. ROBERTS, OF ITHACA, MICHIGAN.

GAME APPARATUS.

1,184,572.

Specification of Letters Patent. Patented May 23, 1916.

Application filed August 6, 1915. Serial No. 44,007.

To all whom it may concern:

Be it known that I, WILLIAM A. ROBERTS, a citizen of the United States, residing at Ithaca, in the county of Gratiot and State 5 of Michigan, have invented certain new and useful Improvements in Game Apparatus; and I do hereby declare the following to be a full, clear, and exact description of the invention, such as will enable others skilled 10 in the art to which it appertains to make and use the same.

This invention relates to game apparatus, and one of the principal objects of the invention is to provide a game board and 15 game pieces which may be used in playing a game to simulate war between two or more nations, and which will be interesting, amusing and which will require considerable skill and calculation on the part of the 20 players to properly play the game.

The foregoing and other objects may be attained by means of the construction illustrated in the accompanying drawings, in which—

25 Figure 1 is a top plan view of a game board made in accordance with this invention, Fig. 2 is a portion or field of the game board shown enlarged, Fig. 3 is a side view of one of the game pieces, a cavalryman, Fig. 4 is a perspective view of another one 30 of the game pieces, a picket, Fig. 5 is a plan view of another game piece, an aeroplane, Fig. 6 is a perspective view of a general, Fig. 7 is a side elevation of one of the game 35 pieces, a rapid fire gun, and Fig. 8 is a side elevation of a siege gun.

Referring to the drawings, the numeral 1 designates the game board, which is preferably rectangular in form and of the required size for its purpose. Upon the face 40 of the board are diagonal lines 2, which extend from one corner diagonally across to the opposite corner, and cross at the center at 3. Lines 4 extend across the board at right angles and intersect at the point 3 in the center to divide the board into four equal squares. In the center of each of the four sides of the board is a panel to represent a capital, and the word "Capital" may 45 be indicated thereupon or adjacent thereto, as shown in Fig. 3. The capitals are indicated by the numeral 5. Five semi-circular lines, 6, 7, 8, 9, and 10 inclose the capitals, said lines being spaced apart equally 55 and being of greater radii progressively from the "capitals" toward the center of the

board. On the inner side of the semi-circle 6 are four panels or squares, 11, 12, 13 and 14. There are five large circles displayed on the board and within the four 60 circles spaced from the center are smaller circles 16, while within the central circle two bobbin-shaped figures 17 are arranged, one at right angles to the other. Within each of the circles, squares 18 are displayed. 65 Lines or roads 19 lead from one of the corners of the squares 18 to the capitals 5 and lines or roads 20 lead from the junction of two of the circles to spots on the semi-circular lines 8. Other short lines or roads are 70 indicated on the board. Spots representing the positions of the game pieces are made at the intersections of the lines and will be hereinafter referred to.

The game pieces are each provided with 75 a base 21, and as shown in Fig. 3, the game piece is a cavalryman mounted on a horse and is indicated, generally, by the numeral 22. As shown in Fig. 4, the game piece represents a picket and is indicated by the numeral 23. As shown in Fig. 5, the game piece represents an aeroplane and is indicated by the numeral 24. The general 25 is shown in Fig. 6. The rapid fire gun 26 is shown in Fig. 7, and the siege gun 27 is 85 shown in Fig. 8.

Each player has fifteen pieces,—five pickets, two cavalrymen, two rapid fire guns, two siege guns, two aeroplanes, and two generals. Two, three or four persons may 90 play the game. The five pickets are placed on the spots 12 and 13, and the three spots designated by the numeral *p*. The two cavalrymen for each player, are located on the spots indicated by the letter *c*. The rapid 95 fire guns are placed upon the spots *r*. The aeroplanes are placed upon the spots *a* and the two generals are placed upon the spots *g*. The game may be played in several ways. The siege guns are placed upon the squares 11 and 14, as indicated by the letter *s*. The simplest and easiest game is played by two persons, each taking a capital, either opposite or adjacent. The object of the game is to capture your opponent's capital or your 100 opponent's capitals and the game is won when this has been accomplished. A capital is captured when an opponent moves into it and cannot be removed by his rival's next move. Each game piece, except the pickets, can 105 move either backward or forward, toward or from the "capital." The pickets can only 110

- move one spot at a play. The cavalrymen can move three spots either on the lines or circles, or both. The rapid fire guns can be moved two spots on the lines or circles, or both. The siege guns move any distance on straight lines. The generals can move two spots on straight or broken lines, and the aeroplanes can move two spots on circular lines. No game piece can pass another piece on a line or circle, but must have a free move. Each piece must make its complete move, that is to say, a general must move two spots. Each piece has the power to capture an opponent's piece provided the opponent's piece rests on a spot at the limit of movement of said piece.
- From the foregoing it will be obvious that a game played on this board will be interesting, will require considerable skill on the part of the players, and judgment must be used in order to be successful in winning the game. The various movements of the game pieces may be made to closely simulate the game of war.
- Various changes may be made in the details of construction and the manner of playing the game without departing from the spirit and scope of the invention as defined in the claims.

30 What is claimed is:—

1. A game apparatus comprising a rectangular board having represented on the surface thereof a series of semi-circular concentric lines at each of its four sides, 35 a capital inclosed within each of the smaller

semi-circles, circles, squares and other figures on the board partly within and partly without the areas inclosed by the semi-circles and spots at the intersection of the lines of such figures, and game pieces adapted to be moved about the board, the movement of the game pieces being governed by the relative value of the game pieces and by the lines on the board, said game pieces being figures of various persons and implements used in the wars of nations.

2. A game apparatus comprising a rectangular board having upon its surface a series of semi-circles, circles, squares and angular lines or roads partly within and partly without the areas inclosed by the semi-circles, capitals being indicated at the center of each of the four sides of the board, spots at the intersection of some of the lines on the board, and game pieces comprising cavalrymen, pickets, generals, rapid fire guns, siege guns, and aeroplanes, the game being played by moving the game pieces about the board with a view to capturing the capitals, the movement of the game pieces being governed by the relative value of the game pieces and by the lines on the board.

In testimony whereof I affix my signature in presence of two witnesses.

WILLIAM A. ROBERTS.
